UNITED STATES PATENT OFFICE.

HARVEY D. GEYER, OF DAYTON, OHIO, ASSIGNOR, BY MESNE ASSIGNMENTS, TO THE INLAND MANUFACTURING COMPANY, OF DAYTON, OHIO, A CORPORATION OF DELAWARE.

PRESSED-METAL SPIDER HAVING CROSSED ARMS.

Application filed May 3, 1922. Serial No. 558,054.

To all whom it may concern:

Be it known that I, HARVEY D. GEYER, a citizen of the United States of America, residing at Dayton, county of Montgomery, 5 and State of Ohio, have invented certain new and useful Improvements in Pressed-Metal Spiders Having Crossed Arms, of which the following is a full, clear, and exact description.

10 This invention relates to handwheels and embodies certain improvements in the construction disclosed in my copending application, Serial No. 529,914, filed January 17, 1922.

15 An object of this invention is to provide a handwheel which is very cheap to manufacture and yet is of sturdy construction and good appearance.

20 Among the more specific objects is to construct the spider of pairs of pressed metal arms which lap over each other at the hub and are secured to the hub by a simple and efficient means.

25 Another object is to form a spider which may be easily expanded for securing it to the rim, after which its rigidity may be increased to cause it to retain its expanded shape.

30 Further objects and advantages of the present invention will be apparent from the following description, reference being had to the accompanying drawings, wherein preferred embodiments of the present invention are clearly shown.

35 In the drawings:

Fig. 1 is a plan view showing one form of embodiment of my invention;

Fig. 2 is a section through the wheel of Fig. 1, but showing one of the spider arms 40 in side elevation;

Fig. 3 is a section on line 3—3 of Fig. 1, showing in full lines the angle of the arm flanges before expanding the spider, and in dotted lines the angle to which the flanges 45 are turned to increase the stiffness of the arms after expanding;

Fig. 4 shows a modified form of arm end for taking the radial pressure of the arm against the rim;

50 Fig. 5 shows another modification of the arm end;

Fig. 6 is a modification wherein the spider is not expanded into the rim but is secured thereto; and

Fig. 7 is a sectional view through the 55 wheel of Fig. 6.

Throughout the several views of the drawings similar reference characters refer to similar parts.

Numeral 10 designates the rim of the 60 handwheel which I have here shown as constructed of coiled wood laminations, however any other form of rim may be used with this invention if desired. The spider, designated in its entirety by numeral 11, is 65 formed of two pressed metal pieces 12 and 13 which are lapped over each other at the center of the wheel, thus forming the arms of the spider. The arm piece 12 is provided with a downwardly turned flange 14 extending 70 all the way across the center portion (see Figs. 1 and 2), while the arm piece 13 has its downwardly turned flange 15 cut off at the points 16 where it abuts the flange 14, thus permitting the arm piece 13 to lie flat 75 on top the arm piece 12 as clearly shown. Both the arm pieces 12 and 13 are preferably widened out at the center as shown, for symmetry and to permit the flanges 14 of the arm piece 12 to encircle the flange 21 80 of the hub 20, which therefore lies snugly up against the bottom of arm piece 12. A clamping plate 22 provided with downwardly turned lugs 23 which extend through suitably provided holes in pieces 12 and 13, 85 as shown, serves to securely fasten the arm pieces 12 and 13 to the hub 20. The ends of the lugs 23 are bent inwardly around the edge of the hub flange 21. Preferably the hub flange 21 is recessed at its periphery 90 for the lugs 23 to pass downwardly therethrough in order to hold the hub 20 against relative rotation. This construction is more clearly shown in Fig. 7. It will be seen that the clamping plate 22 with its projecting 95 lugs constitutes a single integral means for holding together the spider arms and hub in an efficient manner and at the same time avoids any unsightly rivet or bolt heads at the center of the wheel, as is ordinarily the 100 case in pressed steel spiders.

The flanges 14 and 15 of arm pieces 12 and 13 are widened out sufficiently a short distance from the center to permit their being turned inwardly to form the box sections 25 in the spider arms, as shown. These box sections 25 greatly increase the strength of the arms against buckling under the 105

radial pressure exerted upon them when the spider is expanded into the rim, as will be more fully described later. Also the box sections 25 present better appearing spokes, and more convenient means for grasping with the hand as is often done in actual use of steering wheels.

In Figs. 1 and 2 the ends of the arms 25 have the box section cut at the corners and 10 the sides turned inwardly to form shoulders 26 to take the radial pressure of the arm against the rim when the spider is expanded. A modification is shown in Fig. 4 wherein the sides are turned outwardly to form shoulders 26' for the same purpose. After cutting away the sides as described, the top and bottom of the box section 25 form two wide flat projections 27, which are adapted to be inserted into corresponding recesses 28 in 20 the inner periphery of the rim 10 by the expanding of the spider. By making projections 27 of only small thickness and obtaining the necessary strength by their width only very narrow slots 28 will be required 25 in the rim 10 and hence the rim will not be appreciably weakened at those points.

The spider 11 is originally constructed of sufficiently small outer diameter that the ends 27 of the arms may be inserted or 30 placed opposite their corresponding recesses 28 in the rim 10, and then the spider is expanded by any suitable means, one method being described in my previous application, above mentioned, until the shoulders 26 or 35 26', as the case may be, are tightly pressed against the inner periphery of the rim. The arm piece 12 of the spider is originally made with its flange 14 turned downwardly at only a small angle in the vicinity of the section 40 line 3—3 of Fig. 1 (see Fig. 3) in order to permit the easy bending of the piece 12 when the spider is expanded. After the spider is expanded into the rim 10 the flanges 14 are then turned down to the dotted position 14' 45 in Fig. 3, thus greatly stiffening the arm piece 12 and causing it to retain its expanded shape.

Fig. 5 shows a modified method of inserting the arm end into the rim 10. The recess 50 28' for the projections 27 are cut in rim 10 at a diverging angle as shown; when the spider is expanded the projections 27 enter the recesses 28' and are bent apart by following the diverging recesses 28'. In this 55 modification the shoulders 26 or 26' may be entirely dispensed with if desired and the radial pressure of the arm upon the rim be taken by the angularly inclined projections 27.

Figs. 6 and 7 show a modification wherein 60 the spider is fastened to the rim 10 by screws or by any suitable separate attaching means instead of being expanded into recesses in the rim.

The overlapping arm pieces 30 and 31 are

connected together and to the hub 20 by the clamping plate 22 in a similar manner to the spider of Figs. 1 and 2. Hence the central portion of the spider will not be again described in detail. The flanges 32 of the arms 70 are curved around under the arms to form oval shaped sections as shown in Fig. 6 instead of the box section shown in Figs. 1 and 2. Of course either modification could employ either the box or oval section arms 75 as desired. In Figs. 6 and 7 the flanges 32 are cut away near the arm ends and the ends are bent around to fit the rim 10 as shown in Fig. 7. Preferably the ends 33 are given slightly more curvature than the rim 10 so 80 they will bear against the rim at only two points and the middle portion will act as a spring to hold the screws 34 tight at all times and prevent them from loosening and rattling. In all modifications described 85 herein the hub 20 may be attached to its shaft by means of a key or other suitable means, and a nut or bolt head bearing against clamping plate 22 may hold the handwheel on its shaft, as will be clearly 90 understood by those skilled in the art.

While the forms of mechanisms herein shown and described, constitute preferred forms of embodiments of the present invention, it is to be understood that other forms 95 might be adopted, all coming within the scope of the claims which follow.

What I claim is as follows:

1. A wheel spider including a hub portion, a plurality of pairs of metal arms 100 lapped over each other at the hub, and a metal plate for clamping the arms to the hub portion, said plate having projections integral therewith which are bent around part of the hub.

2. A wheel spider including a hub portion, a plurality of pairs of metal arms lapped over each other at the hub, and a metal plate for clamping the arms to the hub portion, said plate having clamping lugs 110 which extend through holes in the arms.

3. A wheel spider including a hub having a flange, a plurality of pairs of metal arms lapped over each other at the hub, and a single means for clamping the arms 115 to the hub flange, said means having lugs integral therewith which extend through holes in the arms and are then bent around the flange.

4. A wheel spider including a hub, a plurality of pairs of flanged metal arms lapped over each other at the hub, the flanges of all except one pair of arms being cut away where the arms cross to permit the arms to lie in close contact with each other and a malleable metal member for clamping the arms to the hub.

5. A wheel spider including a hub, a plurality of pairs of flanged metal arms lapped over each other at the hub, the flanges of all 130

except one pair of arms being cut away where the arms cross to permit the arms to lie in close contact with each other and with the hub, and means for securing the 5 arms to the hub.

6. A wheel spider including a plurality of pressed metal arms, said arms having comparatively narrow flanges near the center to permit easy bending of the arms for 10 the purpose of expanding the spider, and comparatively wide flanges at a distance from the center to increase the compressive strength of the arms.

7. A handwheel having a rim and metal 15 spider, the arms of said spider being of relatively narrow depth near the hub to permit easy bending and of greater depth at other points to carry radial compression, the ends of the arms being held in tight 20 contact with the rim by forcibly spreading the spider.

8. A handwheel having a rim and a spider, said spider including a plurality of pairs of arms lapped over each other at 25 the hub, one of said pairs of arms being flanged across its central portion to give stiffness to the spider, the ends of the arms being adapted to be forcibly projected against the rim by expanding the spider.

30 9. In a handwheel, a spider having flanged pressed metal arms with depending flanges, a rim having recesses in its inner periphery into which the outer ends of the arms are adapted to be projected by force-

bly expanding the spider to increase its 35 outer diameter, and shoulders adjacent the outer ends of the arms formed by bending the arm flanges at an angle to the arm.

10. The steps in the construction of a handwheel comprising, expanding a metallic spider to cause the outer ends of its arms to be forcibly pressed against the rim of the handwheel, and then while said spider is held in expanded position increasing 40 the rigidity of the spider arms to cause 45 them to retain the expanded position.

11. The steps in the construction of a handwheel comprising, expanding a metal spider to cause the outer ends of its arms to move into suitable recesses in a rim, and then turning down a flange on each of said arms to increase the rigidity thereof to prevent return to non-expanded position.

12. The steps in the construction of a handwheel comprising, expanding a metal 55 spider to cause the outer ends of its arms to be forcibly pressed against the rim of the handwheel, and then increasing the rigidity of said arms by turning down 60 flanges on said arms while they are held in expanded position.

In testimony whereof I hereto affix my signature.

HARVEY D. GEYER.
